CLAIM

We claim the ornamental design for a reversible coupling plush toy, as shown and described.

DESCRIPTION

This application is related to U.S. application Ser. No. 17/325,659 entitled “Reversible Toy With Coupling Appendages” filed on May 20, 2021 and incorporated by reference herein in its entirety.

FIG. 1 is an isometric view of a reversible coupling plush toy showing the reversible coupling plush toy in a first configuration.

FIG. 2 is a front elevation view of the reversible coupling plush toy of FIG. 1.

FIG. 3 is a rear elevation view of the reversible coupling plush toy of FIG. 1.

FIG. 4 is a left side elevation view of the reversible coupling plush toy of FIG. 1.

FIG. 5 is a right side elevation view of the reversible coupling plush toy of FIG. 1.

FIG. 6 is a top plan view of the reversible coupling plush toy of FIG. 1.

FIG. 7 is a bottom plan view of the reversible coupling plush toy of FIG. 1.

FIG. 8 is an isometric view of the reversible coupling plush toy of FIG. 1 in a second configuration.

FIG. 9 is a front elevation view of the reversible coupling plush toy of FIG. 8.

FIG. 10 is a rear elevation view of the reversible coupling plush toy of FIG. 8.

FIG. 11 is a left side elevation view of the reversible coupling plush toy of FIG. 8.

FIG. 12 is a right side elevation view of the reversible coupling plush toy of FIG. 8.

FIG. 13 is a top plan view of the reversible coupling plush toy of FIG. 8.

FIG. 14 is a bottom plan view of the reversible coupling plush toy of FIG. 8.

(Continued)

FIG. 15 is a front elevation view of the reversible coupling plush toy of FIG. 1 coupled to a second reversible coupling plush toy that is in a first configuration.

FIG. 16 is a front elevation view of the reversible coupling plush toy of FIG. 8 separated from the second reversible coupling plush toy of FIG. 15 that is in a second configuration; and,

FIG. 17 is a front elevation view of the reversible coupling plush toy of FIG. 8 separated from the second reversible coupling plush toy of FIG. 15.

The differently shaded stippled areas indicate different color surfaces of the reversible coupling plush toy but are not intended to indicate specific colors.

The broken lines immediately adjacent to the shaded stippled areas depict the bounds of the claimed design, while all other broken lines including those which cross over the fill line showing features are directed to environment and form no part of the claimed design.
